UNITED STATES PATENT OFFICE.

HENRY F. CRYER, OF HARTSELLS, ALABAMA.

TORPEDO FIRE ALARM.

Application filed March 30, 1925. Serial No. 19,457.

This invention has reference to a fire alarm, the primary object of the invention being to provide a torpedo which may be fired by the heat of the burning building or room in which the device is positioned, thereby causing an audible signal to be made.

Another object of the invention is to provide a device of this character which may be readily and easily positioned at places where fires are liable to occur.

A still further object of the invention is to provide an alarm of this character which will be exceptionally cheap to manufacture and one which will cause a loud signal to be made, when the signaling device is operated.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a signaling device constructed in accordance with the invention.

Figure 2 is a sectional view taken on line 2—2 of Figure 1.

Figure 3 is a sectional view taken on line 3—3 of Figure 2.

Referring to the drawing in detail, the reference character 5 indicates the body portion, which is tubular in formation and formed preferably of compressed paper, however it is to be understood that any suitable material may be employed in the construction of the body portion without departing from the spirit of the invention.

An opening indicated at 6 is formed in the body portion and disposed intermediate its ends, which opening is designed to accommodate and support one end of the fuse 7, forming part of the invention.

The reference character 8 indicates powder or other explosive material, which powder is

poured into the body portion from the ends thereof in such a way that the powder will surround the fuse 7, as clearly shown by Figure 2 of the drawing. Paper plugs are positioned in the ends of the body portion and engage the explosive material 8 to hold the explosive material in proper position, around the fuse.

Positioned over the ends of the body portion are caps 10 which may be secured to the body portion in any suitable manner. Secured to the caps 10 are tabs 11 which are provided with openings 12 through which a suitable securing nail or screw may be positioned to support the body portion on the wall of a building or other suitable support.

The fuse is of the usual construction and is formed with a longitudinal opening for the reception of powder which will become ignited under intense heat, to cause the explosive material 8 to be fired causing a signal to be made.

In order that the fuse will be protected from the elements, a thin layer of celluloid is secured over the body portion and outer end of the fuse, so that under intense heat, the celluloid will become ignited to fire the fuse to ignite the explosive material 8.

I claim:

In a signaling device, a cylindrical body portion adapted to contain an explosive material, said body portion having an opening 80 in its wall and disposed intermediate its ends, a tubular member having one end thereof disposed within the opening and having its opposite end terminating at a point substantially centrally of the body portion, a fuse positioned within the tubular member and extending throughout the length thereof, and a protecting strip secured to the body portion and disposed over the opening and outer end of the tubular member and 90 fuse.

In testimony that I claim the foregoing as my own, I have hereto affixed my signature.

HENRY F. CRYER.
